WHEEL FOR CHAIRS

Edward C. Thornton, Youngstown, Ohio

Application March 9, 1942, Serial No. 433,965

1 Claim. (Cl. 280—61)

This invention relates to wheels for chairs and more particularly to a portable wheel and axle assembly adapted to be positioned beneath the rockers of a rocking chair or in under the back legs of a straight chair in order to facilitate the movement of the chair and an occupant.

The principal object of the invention is the provision of a portable wheel and axle assembly adapted to carry a chair.

A further object of the invention is the provision of a wheel and axle assembly provided with separate and distinct means for engaging either the rockers of a rocking chair or the back legs of a straight chair in order to facilitate the movement of the same thereby.

A further object of the invention is the provision of a wheel and axle assembly so formed as to be adjustable as to width so as to make the same adaptable for use upon rocking chairs or straight chairs of varying widths.

A still further object of the invention is the provision of a wheel and axle assembly for lending portability to straight chairs and including means formed thereon against which the back of a straight chair contacts in order to insure the positive location of the straight chair on the device.

The wheels for chairs shown and described herein have been designed to facilitate the moving about of invalids or primarily those temporarily ill and confined to a chair. As is well-known, it has heretofore been necessary to either carry the chair and occupant about the premises or buy or rent an expensive wheel chair of the construction well-known in the art and familiar to the general public and which wheel chair, due to the large wheels commonly employed, often encourages the occupant to move about the premises by manually manipulating the large wheels so as to cause the wheel chair to roll and thereby placing an undue strain upon the occupant. The present invention relates particularly to a simple wheel and axle assembly wherein underslung portions of the axle are adapted to receive either the rockers of a rocking chair or the back legs of a straight chair so that the chair may be tilted backwardly upon the wheels of the device and easily and conveniently rolled about the premises thus lending portability to the chair and occupant. Due to its size and use, it makes movement of the chair by the occupant an impossibility and thereby insures against such undesirable action.

With the foregoing and other objects in view which will appear as the description proceeds,

the invention resides in the combination and arrangement of parts and in the details of construction hereinafter described and claimed, it being understood that changes in the precise embodiment of the invention herein disclosed, can be made within the scope of what is claimed without departing from the spirit of the invention.

The invention is illustrated in the accompanying drawing, wherein:

10 Figure 1 is a side elevation of a rocking chair tilted back into position upon the device of the invention.

Figure 2 is an elevation of the device of the invention with parts being broken away.

15 Figure 3 is a top plan view of the invention.

Figure 4 is a side elevation of the invention being used with a straight chair positioned thereon and tilted backwardly.

By referring to Figures 2 and 3 of the drawing, 20 it will be seen that the invention comprises an axle formed of two sections 10 and 10A each section being provided with an underslung portion 11 and 11A, respectively, each of which underslung portions 11 and 11A is in turn provided with rocker receiving members 12 and 12A, each of the rocker receiving members 12 and 12A is provided with cupped chair receiving portions 13 and 13A, respectively.

Conventional rubber tired wheels are indicated 25 at 14 and 14A and by referring to the central-most section of the axle assembly, it will be observed that the portion 10 of the axle is adapted to receive in a slideable manner a smaller portion 15 forming in effect an extension of the axle portion 10A. A band 16 is preferably welded or otherwise affixed about the end section of the axle portion 10 and a thumb screw 17 is fitted in a drilled and tapped opening therethrough and adapted to engage, upon being turned inwardly, 30 35 portion 10A. A band 16 is preferably welded or otherwise affixed about the end section of the axle portion 10 and a thumb screw 17 is fitted in a drilled and tapped opening therethrough and adapted to engage, upon being turned inwardly, portion 10A. As will be understood by referring to Figures 2 and 3 of the drawing, the construction thus described permits the wheel and axle assembly to be extended 40 transversely if desired or narrowed transversely 45 in order that the rocker receiving members 12 and 12A or the chair leg receiving members 13 and 13A, respectively, may be brought to desirable position with respect to the rockers or back legs of the chair under which and in connection with which the wheel and axle assembly is to be used.

It will be seen by referring to Figure 3 that the rocker receiving members 12 and 12A engage the rockers of a rocking chair sufficiently to insure the chair's safe positioning thereon such

as, for example, as indicated in Figure 1 wherein a rocking chair 22 having rockers 23 thereon is shown in position upon the device. It will be obvious that in order to position the rocking chair upon the device, the chair has been tilted forward, the device moved in under the rockers so that the rocker receiving members 12 and 12A, respectively, come into engagement with the rockers 23 and that by then tilting the rocker backwardly the chair may be safely balanced upon the wheel and axle assembly and moved about the premises as desired.

By again referring to Figures 2 and 3 of the drawing, it will be observed that in order to adapt the assembly for use in straight chairs, the axle portion 10 has been provided with a socket member 18 which is preferably welded or otherwise affixed thereto so that it is in effect centrally located between the wheels 14 and 14A, respectively, and an upwardly extending lever arm 19 is positioned in the socket member 18 and pivotally affixed therein by means of a thumb screw 21, the uppermost end of the lever arm 19 preferably being provided with a cross member 20 which may be of any width desired so that it is sufficient to engage a portion of the back of a straight chair as may be seen by referring to Figure 4 wherein a straight chair 24 provided with back legs 25 has been positioned on the device, the lowermost portions of the back legs 25 engaging the members 13 and 13A, respectively, and the lever arm positioned so that it extends upwardly with the cross piece 20 thereof engaging the back of the chair in a manner so that the chair may be effectively balanced between the same and the members 13 and 13A which, it will be observed, are formed off center with respect to the transverse axle line of the device. The straight chair 24 therefore by resting upon the members 13 and 13A in front of the axle lines as shown in Figure 4, cause the lever arm 19 and its cross piece 20 to move into engagement with the back of the chair and thus insure the safe

and secure positioning of the straight chair 24 on the wheel device.

It will be obvious that at such time as the device is used with a rocking chair, the lever arm 19 may be dispensed with but that at such times that it is used with a straight chair it is essential that it be used.

Modifications within the scope of the invention obviously contemplate the formation of the wheel and axle assembly from various materials such as castings, forgings, and tubular materials both round and square and otherwise shaped and, it will be obvious that the rocker engaging members 12 and 12A may be surfaced with an abrasive material if desired or might themselves be formed in a slight curve in order to accurately match the rocker surface they will engage. It will also be obvious that the device may be formed by one underslung portion rather than causing the central most section of the axles 10 and 10A to be formed upon the same line as the end sections thereof upon which the wheels 14 and 14A are carried.

Having thus described my invention, what I claim is:

The combination of a straight chair having a back and legs and wheel and axle assembly therefor, the said wheel and axle assembly comprising an axle having wheels mounted on the opposite ends thereof and provided with underslung cupped members positioned forwardly thereof and adapted to receive the back legs of the said chair, a projecting bracket formed on the said axle midway between the said ends thereof and forwardly thereof, a lever arm affixed to the said projecting bracket and extending upwardly therefrom and adapted to engage the back of the said chair positioned on the device, the location of the cupped leg receiving portions and the projecting bracket carrying the said lever arm causing the said chair to maintain its position on the said device when supported manually by the back thereof.

EDWARD C. THORNTON.
